UNITED STATES PATENT OFFICE.

AAGE JENSEN, OF PHILLIPS, WISCONSIN.

MATCH-BOX.

1,282,696.

Specification of Letters Patent. Patented Oct. 22, 1918.

Application filed April 20, 1917. Serial No. 163,449.

To all whom it may concern:

Be it known that I, AAGE JENSEN, a citizen of the United States, residing at Phillips, in the county of Price and State of Wisconsin, have invented certain useful Improvements in Match-Boxes, of which the following is a specification, reference being had therein to the accompanying drawing.

The present invention relates broadly to improvements in that class of inventions known as special receptacles and more particularly has reference to an improved match box of the single delivery type.

As the primary aim and object the present invention contemplates the provision of novel means mounted within the body of the receptacle and operable simultaneously with the delivery means for agitating the matches as they approach the delivery means so as to insure of the passage of at least one of the matches to the delivery means.

More particularly, the present invention embraces the provision of novel means slidably mounted in the front end of the body of the receptacle for delivering matches one at a time through the exit opening.

It is an additional object of the present invention to provide a resiliently mounted follower in the bottom of the receptacle, improved means being formed on the body and in one side wall of the receptacle for removably locking the follower in a closed position to permit of the filling of the body of the receptacle with matches.

More specific objects of the present invention include the improved means for operably connecting the oscillating shutters with the ejecting slide; to construct the bottom of the receptacle and the cover to assure of the passage of only one match through the exit opening during the operation of the ejecting slide; and to provide improved means for guiding the matches toward the front end of the casing.

Among the other aims and objects of the present invention may be recited the provision of a device of the character mentioned with a view to compactness, and in which the number of parts are few, the construction simple, the cost of production low and the efficiency high.

Other improvements and novel details in the construction and arrangement of the various parts of the apparatus will be brought out more in detail in the description to follow, which for a clear understanding of the

invention, should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the spirit of the invention or the principle of operation of the various parts.

The preferred embodiment of this invention is clearly illustrated in the accompanying drawings, in which:

Fig. 1 is a perspective view of the device embodying the invention.

Fig. 2 is a longitudinal section.

Fig. 3 is a transverse section taken on line 3—3 of Fig. 1.

Fig. 4 is a vertical section taken on line 4—4 of Fig. 1 in the direction in which the arrows point.

Fig. 5 is a vertical section taken on line 5—5 of Fig. 1 in the direction in which the arrows point.

Fig. 6 is a fragmentary perspective detail of the agitating means.

Similar characters of reference are employed in all of the above described views, to indicate corresponding parts.

Referring now, more particularly, to the accompanying drawings there is provided an improved match box or receptacle consisting of a hollow rectangular body indicated in its entirety by the numeral 1 on the top of which is hingedly mounted a flanged cover 2 having an exit opening 3 therein through which matches are adapted to be delivered one at a time. The outer surface 90 of the cover is depressed at an incline as indicated at 4 toward the opening 3 for a purpose that will presently appear. The bottom 5 of the receptacle is inclined toward the front end wall 6 to facilitate the movement of the matches 7 toward the front end.

With a view toward forcing matches toward the front end of the casing an improved follower 8 is provided being arcuate in cross section and arranged vertically in 105 the casing. The helical coil springs 9 have their inner ends carried by the rear end wall 10 of the body of the receptacle and their opposite ends bearing against the follower, the tension of the springs being such as to 110 force the followers toward the front end to consequently correspondingly move the

matches. In order to releasably retain the follower in an inactive position the side walls of the body of the receptacle are provided with opposed horizontal slots 11 each having a right angularly projecting terminal 12 adjacent the rear wall 10. Knobs 13 are carried by the marginal edges of the follower and project through the adjacent slots and are normally slidable through the main portions 11 thereof but when the follower knobs are moved upwardly into the angularly projecting portions of the slots the springs 9 will cooperate therewith in maintaining the follower in such position to consequently prevent movement of the follower.

For the purpose of guiding the matches toward the front end wall of the body improved guiding means are provided in the present instance being formed desirably from a blank of sheet metal which is bent into a substantially V-shaped form in cross section forming opposed divergent guides 14. The vertex 15 of the guiding means is arranged in spaced parallel relation with the inner surface of the end wall 6 and vertically and medially thereof so that the opposed guides or arms direct the matches toward the vertex. The space between the inner ends of the guide is such that only one match may be accommodated therein.

With a view toward providing improved means for ejecting matches from the body and delivering them through the opening 3 the front wall 6 is provided with a vertical slot 16 through which is slidably projected a finger piece 17 formed on the body 18 of the vertical slide. A leg 19 depends from the body of the slide in spaced parallel relation to the end wall 6 while a lifting foot 20 is formed on the extreme inner end thereof, the foot being arranged for vertical sliding movement in a vertical slot 21 in the inner end of the blank of the guiding means or member. This slot is preferably provided by removing a portion of the vertex 15 on the upper end of the slot and serves as a means for limiting the outward movement of the slide. Suitable means such as a coil spring 22, the respective ends of which are connected to the body 18 of the slide and the bottom 5 serves to automatically return the slide to its lowermost position. By the arrangement thus described it will be appreciated that when a match is arranged above the foot 20 the finger piece 17 is moved upwardly through the slot 16 against the tension of the spring 22 and by reason of the fact that the vertex 15 is arranged in registration with the opening 3 the match carried by the foot 20 will be projected through the opening.

As intimated, improved means have been provided for agitating the matches to assure of the forcing of one match on the foot 20. In reducing this feature of the invention to

practice the guides 14 are provided with opposed vertical slots 23 in the upper and lower ends of which are journaled trunnions 24 which project from the respective ends of the agitating blades 25, the trunnions, of course, serving to permit of oscillatory movement of the blades. In order to operably connect the blades with the body 18 of the slide so that the blades will be oscillated in different directions simultaneously with the actuation of the slide, relatively short links 26 are pivoted through the medium of suitable fastening devices 27 to the sides of the body 18 and when the body 18 is in its lowermost position the links are extended upwardly at an incline and loosely connected as at 28 to the outer marginal edge of one of the oscillating blades 25. Longer links 29 are also provided and have their inner ends pivoted by suitable fastening devices 30 to the opposite side of the body in spaced relation to each other and when the body is in a position indicated in Fig. 2 the links 29 extend downwardly and are loosely connected to the inner marginal edges of the other oscillating blade 25 as indicated by the numeral 31. By this arrangement when the slide is raised upwardly owing to the relatively short links 26 the blade 25 to which they are connected will be oscillated outwardly during the upward movement while the other blade 25 connected to the slide by the link 29 will be moved inwardly but on the lowering of the slide the operation will be the reverse.

In use, assuming that the parts have been assembled in the manner described and it is desired to remove a match from the box the finger piece 17 is raised to raise the slide and the foot 20 upon which one of the matches 7 is positioned. The single match on the foot will be carried upwardly thereby and projected through the exit opening 7. The inclined depressed surface 4 of the cover serves to prevent the passage of more than one match through the opening 3. During the raising of the slide owing to the arrangement of the links the blades 25 will be oscillated in opposite directions to assure of a movement of the matches toward the forward end thereby preventing binding of the matches in the body. Upon release of the slide it will be automatically returned to its normal position by the spring 22. It is to be appreciated of course that the resilient follower normally serves to force the matches toward the guides 14 which direct the matches singly toward the vertex so as to consequently arrange a single match above the foot 20.

As many changes could be made in the above construction and many apparently widely different embodiments of this invention could be made without departing from the scope thereof, it is intended that all

matter contained in the above description or shown in the accompanying drawings shall be interpreted as illustrative and not in a limited sense. It is also to be understood 5 that the language used in the following claims is intended to cover all the generic and specific features of the invention herein described and all statements of the scope of the invention, which as a matter of language 10 might be said to fall therebetween.

Having thus fully described this invention, what is claimed as new and desired to be secured by Letters-Patent, is:—

1. A match box including a body, a cover therefor and having a match exit opening therein, resiliently mounted follower means in the body, opposed vertical diverging guides mounted adjacent the front end of the body and spaced at their outer ends 15 to accommodate only one match therebetween and being formed with opposed vertical slots, coöperative agitating means journaled for oscillatory movement in the upper ends of the slots and arranged in the 20 path of movement of the matches between the guides, ejecting means slidably mounted for vertical movement in the front end of the body and operating between the guides so as to raise a single match and project it 25 through the opening in the cover and operably connected with the agitating means to oscillate the latter simultaneously therewith. 30

2. A match box including a hollow rectangular body, a cover therefor and having a match exit opening therein, a resiliently mounted follower in the body, coöperative means formed on the follower and in the body for removably holding the follower in an inactive position, opposed diverging 35 guides mounted adjacent the front end of

the body and spaced therebetween, ejecting means slidably mounted in the front end of the body and operating between the guides so as to raise a single match and project it 45 through the opening in the cover, the guides being provided with opposed vertical slots, agitating blades, trunnions formed on the respective ends thereof and journaled in the respective ends of the slots to permit of oscillation of the blades, and links having 50 their respective ends connected to the agitating means and to the oscillating plates so that the plates will be oscillated in different directions simultaneously with the actuation of the ejecting means to consequently prevent clogging of the matches in the body. 55

3. A match box including a hollow rectangular body for receiving matches, a cover for the body and having an opening therein, means mounted within the body for forcing matches toward the front end thereof, the front end of the body being provided with a vertical slot, a slide mounted for vertical sliding movement adjacent the front end of the body, a leg depending therefrom, a lifting foot formed on the lower end of the leg, a finger engaging piece extending from the slide and projecting through the slot, guiding means mounted vertically in the body adjacent the slide and constructed to accommodate only one match at the inner end and also constructed to slidably receive the lifting foot whereby when the finger piece is moved upwardly a single match positioned at the inner end of the guiding means will be 60 engaged by the foot and projected through the opening in the cover. 65

In testimony whereof I affix my signature.

AAGE JENSEN.
